US0D1020154S

(12) **United States Design Patent** (10) **Patent No.:** **US D1,020,154 S**
(45) **Date of Patent:** **** Mar. 26, 2024**

(54) **CLEANING DEVICE**

- (71) Applicant: **The Procter & Gamble Company**, Cincinnati, OH (US)
- (72) Inventors: **William Michael Cannon**, Harrison, IN (US); **Richard Christopher Hagee**, Cincinnati, OH (US); **Victoria Jung**, Cincinnati, OH (US); **John Charles Van Rens**, Cincinnati, OH (US); **Kerry Lloyd Weaver**, Florence, KY (US)
- (73) Assignee: **The Procter & Gamble Company**, Cincinnati, OH (US)
- (**) Term: **15 Years**
- (21) Appl. No.: **29/841,075**
- (22) Filed: **Jun. 2, 2022**

Related U.S. Application Data

- (63) Continuation of application No. 29/813,426, filed on Oct. 28, 2021, now Pat. No. Des. 957,773, which is a continuation of application No. 29/723,643, filed on Feb. 10, 2020, now Pat. No. Des. 937,520.
- (51) **LOC (14) Cl.** **07-05**
- (52) **U.S. Cl.** **D32/45**
- (58) **Field of Classification Search**
USPC D32/45, 50-51
CPC A47L 13/22; A47L 13/20; A47L 13/256
See application file for complete search history.

(57) **CLAIM**

The ornamental design for a cleaning device, as shown and described.

DESCRIPTION

FIG. 1 is a perspective view of an embodiment of a cleaning device embodying our new design;

FIG. 2 is a front view thereof;

FIG. 3 is a left view thereof;

FIG. 4 is a back view thereof;

FIG. 5 is a right view thereof;

FIG. 6 is a top view thereof; and,

FIG. 7 is a bottom view thereof.

Any broken lines shown in the drawings are for illustrative purposes only and form no part of the claimed design.

1 Claim, 4 Drawing Sheets
